UNITED STATES PATENT OFFICE

DALLAS C. CARROLL, OF AKRON, OHIO, ASSIGNOR TO THE FIRESTONE STEEL PRODUCTS COMPANY, OF AKRON, OHIO, A CORPORATION OF OHIO

PUNCH PRESS

Application filed March 27, 1924. Serial No. 702,409.

This invention relates to punch presses and especially to multiple head or gang presses particularly adapted for simultaneously punching a plurality of apertures at spaced points in the periphery of an article, such as a wheel-rim of the attached lug or attached clamp type.

The purpose of the invention is to provide an improved press of simple construction and speedy operation and one which is adapted simultaneously to punch a number of spaced apertures at spaced points in an article, such as a wheel-rim, whereby punching operations are reduced to a minimum and proper spacing of the apertures is assured. More particularly the invention contemplates the arrangement of a number of tool-carrying heads so as to operate upon an article from different sides thereof and means for simultaneously operating the heads to perform a plurality of punching operations at one time.

Another object of the invention is to provide spaced die-blocks for cooperation with the punches and for supporting the article in position for the punching operation. A further object is to provide means on the tool-carrying heads adapted securely to clamp the article in place on the die-blocks as the punching operation is performed and adapted to be withdrawn from such engagement as the punches are withdrawn to permit removal of the finished work and the mounting of another article in the machine.

Other objects will appear from the following detailed description of the press in connection with the accompanying drawings in which the invention is illustrated in its preferred form, it being understood that the drawings and description are for the purpose of illustration only and that the invention is not wholly limited in the claims to the specific embodiment shown.

Of the accompanying drawings:

Figure 1, is a vertical section on line 1—1 of Figure 2.

Figure 2 is a plan, the driving means shown in Figure 1 being omitted.

Figure 3, is an enlarged detail view show-

ing the cooperation with the work of a head and a die-block.

Figure 4, is a section on line 4—4 of Figure 1.

Referring to the drawings, 10 represents a suitable frame formed at one end with an upstanding annular support or table 11 on which is mounted a generally circular casting 12 formed with a central bore 13 and a plurality, in this instance four, spaced inwardly and downwardly sloping guideways 14, 14, the outer ends of which project beyond the generally circular portion of the casting. The center plate 12 may also be provided with suitably formed recesses 15, 15 adapted to receive and support die-block holders 16, 16 which are secured in the recesses 15 in any suitable manner as by stud bolts 17, 17. The die-holders 16 are adapted to have removably secured therein, die-blocks 18, 18 having die-apertures 19, 19 therein (Fig. 3), the holders 16 being apertured, as at 20, 20 to permit punchings to fall from the machine. For clamping the die-blocks in the holders, clamping plates 21, 21 are provided, the plates being clamped onto the die-blocks by nuts 22, 22 on the stud bolts 17. The spaced die-blocks are adapted to support an article such as a rim thereon in position for a punching operation.

Each guideway 14 is formed with an undercut guide groove 23, the groove being defined on one side by an adjustable bar 24 secured so as to be horizontally slidable in the groove 23 by cap-screws indicated at 25 inserted through slots in the bars and screwed into the bottom of the groove. For adjusting the bar to vary the width of groove 23, cap-screws indicated at 26 are so operable into the groove from the side of the guideway as to be engageable with the bars.

Arranged for reciprocatory movement in each guideway is a sliding head 27 formed with a lower dove-tail portion 28 engaged in the guide-groove 23. Removably secured to each head 27 is a punch holder 29, the latter being secured to the head in any suitable manner as by cap-screws 29^a, 29^a. A

slot 30 is provided in each holder 29 for the reception of a punch 31 which is adapted to be secured therein by a notch 32 formed in one side thereof, a set screw 33 being threaded through a bore in the holder into engagement with the notch. On the top of each head 27 is secured, as by stud bolts indicated at 34, a clamping plate 35 formed of a flat strip of metal which projects beyond the inner end of each head and has an upwardly curved inner end adapted to engage the work, such as the rim denoted R, as the punching operation is performed, the engagement being yielding due to the spring of the projecting portion of the metal strip.

To the end that all of the heads 27 will be simultaneously operated in radial reciprocations inwardly and outwardly there is provided a vertical reciprocating rod 36 formed as an eye-bolt the "eye" of which is secured by a pin 37 to a sliding block 38 slidably received in vertical guideways indicated at 39 formed in the frame 10. For reciprocating the rod 36, a connecting rod or pitman 40 is hingedly connected to the pin 37 and to a crank-pin 41 on a crank shaft 42. The crank shaft 42 is adapted to be rotated by a gear 43 driven by a motor 44 through a suitable reduction gear train including gears 45, 46, 47, 48, and 49, the last mentioned gear being on the motor shaft. Adjustably mounted on the rod 36 is a spider 50 having a bore 51 therein for the reception of the rod 36, the spider being formed with an upwardly extending sleeve 52 adapted slidably to fit in the bore 13, a suitable bushing 53 being interposed between the sleeve 52 and the bore. The spider 50 is adjustably secured on the rod 36 by a nut 55 screw-threadedly received on the rod and formed with an enlarged upper portion fitting in a recess 56 in the spider the nut being secured to the spider by a generally annular plate 57 encircling the nut below the enlarged upper portion thereof and secured to the spider by cap-screws 58, 58. The spider 50 is formed with four radiating horizontal arms 59, 59 on which are formed upwardly extending bi-furcated lugs 60, 60, respectively to which are hingedly connected horizontally disposed links 61, 61, the links 61 being in turn connected to the lower ends of bow-shaped levers 62, 62 pivoted to the casting 12 in slots 63, 63 formed in the projecting portion of the guideways 14.

In order that the bow-levers 62 may impart reciprocatory movement to the heads 27, each of the latter is formed with a slotted outer portion 64 (Fig. 4) arranged to receive the upper end of the lever 62. Alined slots 65, 65 are formed in the slotted portion 64 of the head 27 so as loosely to receive a pin 66 secured by set screws 67, 67 in apertures 68, 68 formed in a bi-furcated por-

tion 69 of the upper end of the lever 62. A hardened roller 70 is journaled on the pin 66 between the bifurcations on the upper end of the lever 62 and is adapted to bear on a wear plate 71 secured on the inner end of the slotted portion 64 as the head is advanced so as to bring the tool into engagement with the work, the pressure necessary to punch the rim being imparted to the head 27 by the roller 70.

In operation motor 44 is continuously operated whereby rod 36 is reciprocated vertically to impart vertical reciprocations to spider 50. Vertical reciprocations of spider 50 imparts oscillatory movement to levers 62 which in turn impart reciprocatory movement to all of the heads 27 simultaneously. The movement of the heads 27 is so timed as to enable two operators to remove a finished rim from the machine and insert another in place thereof while the heads are reeded. The rim R is placed upon the die-blocks 18 and as the heads 27 advance inwardly the clamps 35 engage and securely hold the rim in place while the punches 31 are forced through the rim. As the punches recede the clamps 35 are withdrawn, the finished rim is removed and another inserted and so on. Thus a rim is inserted punched and removed upon every complete reciprocation of the heads 27, the speed of the machine being determined by the speed of workmen in the feeding of rims to and removal of finished rims from the machine.

Modifications of the invention may be resorted to without departing from the spirit or scope of the invention. While the machine illustrated is particularly adapted for use in rim manufacture, it will be apparent that it is capable of general application to the manufacture of many other articles for which a gang press may be found to be useful or expedient.

By the term "circumferential series" as used in the appended claims I mean any arrangement of heads adapted simultaneously to operate from and toward different sides of an object no matter what its shape may be.

I claim:

1. A punch press for forming perforations spaced in the periphery of a wheel rim having flanges, said press comprising a table formed with a depression adapted to support a rim therein and with guideways on its periphery sloping downwardly and inwardly toward said depression, punch-carrying heads reciprocably mounted in said guideways whereby perforations may be made adjacent the flanges, and means for simultaneously reciprocating said heads on said guideways.

2. A punch press for forming perforations spaced in the periphery of a wheel rim having flanges, said press comprising a table

formed with a depression adapted to support a rim therein and with guideways on its periphery sloping downwardly and inwardly toward said depression, punch-carrying heads reciprocably mounted in said guideways, means on the heads for clamping a rim in said depression as the heads are moved toward the rim, and means for simultaneously reciprocating said heads.

10 3. A punch press for forming perforations spaced in the periphery of a wheel rim having flanges, said press comprising a table formed with a depression adapted to support a rim therein and with guideways on its periphery sloping downwardly and inwardly toward said depression, punch-carrying heads reciprocably mounted in said guideways, yielding means on the heads for clamping a rim in said depression as the heads are moved toward the rim, and means for simultaneously reciprocating said heads.

4. A punch press for forming perforations spaced in the periphery of a wheel rim having flanges, said press comprising a table formed with a depression adapted to support a rim therein and with guideways on its periphery sloping downwardly and inwardly toward said depression, punch-carrying heads reciprocably mounted in said guideways, means comprising yieldable clamping plates on the heads and projecting inwardly of the heads for clamping a rim in said depression as the heads are moved toward the rim, and means for simultaneously reciprocating said heads.

5. A punch press for forming perforations spaced in the periphery of a wheel rim having flanges, said press comprising means providing a depression adapted to receive and support a rim, a circumferential series of radial guideways about the depression sloping downwardly and inwardly toward said depression, punch carrying heads reciprocably mounted in said guideways and operable to form perforations adjacent a rim flange, and means for simultaneously reciprocating said heads toward and from said depression on said guideways.

6. A punch press for forming rims, said press comprising a support providing a central depression to receive a wheel rim, a circumferential series of die blocks for supporting a rim in said depression, a circumferential series of radial guideways opposite the die blocks and sloping downwardly and inwardly toward said die blocks, punch carrying heads reciprocably mounted on said guideways and cooperating with said die blocks, and means for simultaneously reciprocating said heads on said guideways toward and from said dies.

DALLAS C. CARROLL.
